UNITED STATES PATENT OFFICE.

TIMOTHY McGOLDRICK, OF LINCOLN, NEW HAMPSHIRE.

COAL-SCREEN AND ASH-SIFTER.

1,346,905.

Specification of Letters Patent.

Patented July 20, 1920.

Application filed November 5, 1919. Serial No. 335,921.

To all whom it may concern:

Be it known that I, TIMOTHY McGOLDRICK, a citizen of the United States, residing at Lincoln, in the county of Grafton and State of New Hampshire, have invented certain new and useful Improvements in Coal-Screens and Ash-Sifters, of which the following is a specification, reference being had to the accompanying drawings.

10 This invention relates to a coal screen or ash sifter, and particularly to screens used in households for separating ashes from coal.

15 The general object of this invention is to provide a very simply constructed, easily operated, and effective screening machine of this character wherein the screen, by a simple mechanism is given a longitudinally reciprocating and oscillating motion.

20 A further object is to provide a construction of this character wherein heavier particles of material not passing through the screen are discharged onto an apron for discharge from the casing in which the screen is located.

25 A further object is to provide a machine of this character in which the parts are all housed so that the dust arising from the sifting operation will be confined within the casing.

30 Other objects will appear in the course of the following description.

My invention is illustrated in the accompanying drawings, wherein:—

Figure 1 is a vertical sectional view of a 35 coal screen constructed in accordance with my invention;

Fig. 2 is a section on the line 2—2 of Fig. 1;

Fig. 3 is a sectional view on the line 3—3 40 of Fig. 2;

Fig. 4 is a fragmentary vertical sectional view in the same plane as Fig. 2, but showing a modified manner of mounting the coal screen;

45 Fig. 5 is a fragmentary vertical section through the casing showing the coal screen of Fig. 4 in elevation;

Fig. 6 is a like view to Fig. 5 but showing a modified manner of transmitting power 50 to the coal screen.

Referring to these drawings, and particularly to Figs. 1 to 3, 10 designates a casing, rectangular in cross section, and having a hinged top 11 formed with a central opening for a removable hopper 12.

55 This hopper has a hinged lid 13 at its upper

end. The lower end of the casing 10 is provided with a hinged door 14 whereby the ash box 15 may be withdrawn from the casing. At one point the front of the casing is 60 provided with an opening 16, and below this opening in Fig. 2 there are disposed the upwardly extending tracks 17 formed of angle iron, these tracks extending upwardly and rearwardly. Carried by the forward 65 ends of the trucks and extending out through the opening 16 is an apron or chute 18 supported by an angle iron 19.

Disposed within the casing 10 is a rectangular screen 20 open at the top and having its bottom and sides made of screening material, which is perforated sheet metal, reticulated metal, or the like. This screen is open at its forward end and is provided with rollers 21 mounted upon a transverse rod 22, 70 the ends of which are cranked to receive said rollers, this rod being attached to a supporting screen. The rod preferably extends beneath the screen and the rollers support the screen slightly above the upper surface of 75 the tracks 17. At its rear end, the screen is supported by a crank shaft 23 which extends beneath the screen and has its ends upwardly bent and then outwardly bent and passed through bearings 24 in the side walls of the 80 casing. One extremity of this crank shaft is provided with a crank handle 25 whereby the shaft may be rotated. By rotating the crank shaft, it is obvious that the screen will be reciprocated longitudinally and oscillated 85 vertically upon the fulcrum formed by the wheels 21, and that thus the material within the screen will be given an up and down motion, causing the lighter ashes, cinders, etc., to work downward toward the bottom 90 of the screen and through the screen, while the heavier material works upward toward the top of the screen and at the same time works longitudinally and is eventually discharged upon the apron or chute 18. Thus 95 100 the unburned and partly burned lumps of coal will be discharged from the forward end of the screen onto the apron 18, while the ashes, cinders, and other small like particles will pass through the screen into the 105 ash box 15. It is obvious that it is not necessary to remove the screen in order to discharge the coal therefrom, but that this coal be discharged through the opening 16 as the machine is operated. By opening the 110 cover 11, access to the screen may be had, but ordinarily the material to be screened

will be discharged through the hopper 12 and then the cover closed so as to prevent the upward passage of dust and ashes through the top of the machine.

5 In Fig. 4 I show a modified form of my device wherein the forward end of the screen 20^a is mounted upon a crank shaft 26 connected by a slotted link 27 to the crank shaft 23^a. Otherwise than this, the construction illustrated in Fig. 4 is the same as that illustrated in Fig. 1, but with this form of the invention the forward end of the screen is given an oscillating movement on the forward crank shaft, which I have found 10 extremely effective in separating the coarse and fine particles of ashes and coal and discharging the coal onto the chute or apron 18.

It is obvious that by making the cranks of the crank shafts 23^a and 26 of relatively 20 different lengths, that the rear portion of the screen, for instance, may be given a greater amplitude of movement than the forward portion of the screen, as I have illustrated it, so as to secure a relative oscillation of the screen.

As illustrated in Fig. 6, it is, of course, possible to drive the crank shaft 23 through multiplying gears 28 and 29. It is also 25 obvious that instead of discharging into an

ash box, the casing 10 might discharge directly into a barrel.

While I have illustrated the preferred form of my invention, it will be obvious that minor changes in the details of construction and arrangement of parts might be made 35 without departing from the spirit of the invention.

I claim:—

A screening device of the character described comprising a casing having an opening in its front wall, an apron secured to the casing, and extending through said opening, said apron inclined toward the top of the casing and having extensions on its rear end portions to provide spaced parallel inclined 40 tracks, a screen receptacle disposed between said tracks in spaced relation thereto, said receptacle being open at its top and one end, an axle mounted on the bottom of the receptacle adjacent said open end, rollers on 45 the end of said axle adapted to engage the tracks to movably support the open end portion of said receptacle adjacent the apron, and operating means carried by the other end portion of said receptacle.

In testimony whereof I hereunto affix my signature.

TIMOTHY McGOLDRICK.
